We claim the ornamental design for a cable dock module with sync button for a PDA device, as shown and described.

DESCRIPTION

FIG. 1 is a lower right front perspective view of a cable dock module with sync button for a PDA device showing our new design, with a cable and a PDA device shown in dashed lines and not claimed;

FIG. 2 is a lower right front perspective view of the cable dock module with sync button for a PDA device showing our new design;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.
